[57] CLAIM

The ornamental design for a combined tractor, trailer, helicopter and vehicle toy, substantially as shown.

DESCRIPTION

FIG. 1 is a right side elevational view of a combined tractor, trailer, helicopter and vehicle toy showing my new design;

FIG. 2 is a left side elevational view thereof;

FIG. 3 is a top plan view thereof;

FIG. 4 is a bottom plan view thereof;

FIG. 5 is a front elevational view thereof; and

FIG. 6 is a rear elevational view thereof.
